(57) **CLAIM**

The ornamental design for an eye wear display case, as shown and described.

DESCRIPTION

FIG. 1 is a perspective view of an eye wear display case in accordance with a preferred embodiment of the present invention;

FIG. 2 is a front elevational view of the eye wear display case as shown in FIG. 1;

FIG. 3 is a left side elevational view of the eye wear display case as shown in FIG. 1, with the right side a mirror image thereof;

FIG. 4 is a top plan view of the eye wear display case shown in FIG. 1;

FIG. 5 is a back elevational view of the eye wear display case as shown in FIG. 1; and,

FIG. 6 is a bottom plan view of the eye wear display case as shown in FIG. 1.

The broken lines are for illustrative purposes only and form no part of the claimed design.
